CLAIM

The ornamental design for a case, as shown and described.

DESCRIPTION

FIG. 1 is a front, right side, and top perspective view of a case of our design;

FIG. 2 is a rear, left side, and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the case that form no part of the claimed design.

1 Claim, 8 Drawing Sheets

Related U.S. Application Data

a continuation of application No. 29/660,806, filed on Aug. 22, 2018, now Pat. No. Des. 876,008, which is a continuation of application No. 29/638,723, filed on Feb. 28, 2018, now Pat. No. Des. 860,523.
